(57) **CLAIM**

The ornamental design for an electronic sign, as shown and described.

DESCRIPTION

FIG. 1 is a perspective view of the electronic sign;
FIG. 2 is a perspective view of the opposite side of the electronic sign;

FIG. 3 is a front view of the electronic sign;

FIG. 4 is a rear view of the electronic sign;

FIG. 5 is a side elevation view of the electronics sign;

FIG. 6 is a top side view of the electronics sign; and,

FIG. 7 is a bottom side view of the electronic sign.

The broken lines in the drawings depict environmental subject matter only and form no part of the claimed design.
